[57] CLAIM

The ornamental design for a water ski, as shown and described.

DESCRIPTION

FIG. 1 is a perspective view of a water ski showing my new design;

FIG. 2 is a side elevational view thereof, the side opposite being a mirror image; and,

FIG. 3 is a top plan view thereof.

The unshown bottom of the design is substantially plain and unornamented.

Fig 1.

Fig 2.

Fig 3.
